UNITED STATES PATENT OFFICE.

CHARLES A. HARSCH, OF NEW YORK, N. Y., ASSIGNOR TO WILLIAM H. GARRISON, OF BROOKLYN, NEW YORK.

FIRE-ALARM SIGNALING APPARATUS.

1,247,676.

Specification of Letters Patent. Patented Nov. 27, 1917.

Application filed May 10, 1915, Serial No. 26,920. Renewed April 30, 1917. Serial No. 165,581.

To all whom it may concern:

Be it known that I, CHARLES AUGUST HARSCH, a citizen of the United States, residing in the borough of the Bronx, New York, New York, have invented certain new and useful Improvements in Fire-Alarm Signaling Apparatus, of which the following is a specification.

This invention relates to fire alarm signaling and involves an arrangement of apparatus specially useful in large buildings, having several stories or floors, one above another.

The general arrangement provides for sending signals automatically, either by manual or by automatic initiative, from a signal station on any floor to a main station. The system here described is devised and adapted to meet, and meets, all requirements of the Board of Fire Underwriters of the State of New York and the fire department of the city of New York.

A leading characteristic of this invention is the saving of expense and the simplicity and economy of construction of the mechanism of the sub-station signal box; this is designed to be started into operation by breaking a small sheet of glass in the exposed front, allowing a spring-actuated detent to be withdrawn and a "snap action" or spring-actuated, pivoted switch-arm to be moved from one contact to another. The signal-box mechanism is novel; it has no clockwork, no regulated rotating motor mechanism; its only motor is the helical or other form of spring operating to snap a pivoted contact arm from one contact point or position to another. The motor device usually employed to rotate a circuit-breaking wheel is absent in the structure of this call box. The substitute for this is one single, regulated motor device located at a separate, central point or station. In the form shown, the motor drives a shaft; fixed on this shaft, side by side, are a series or group of circuit-breaking wheels, one wheel for each signal box or station. Usually there are four boxes or substations placed on each floor. It is preferred to place the limit at eight circuit-breaking wheels on one shaft.

In this case, every two floors is provided with a group of eight boxes, associated electrically with a group of eight wheels on a motor-driven shaft. Of course, any series of eight signal stations, wherever located, 55 may be associated with eight wheels or transmitters, driven by a common motor device.

There is a normally closed circuit including a contact in each call or signal box of 60 the group, such contacts being in circuit in series; a special contact in each box has a special branch conductor extending from it directly to the central point or station.

The arrangement of apparatus at the central station includes this motor-driven shaft having the movable members of the transmitters, such as circuit wheels, fixed thereon, side by side; the motor is normally held at rest and at each circuit wheel the complementary contact is a spring contact normally held out of engagement with its circuit-breaking wheel. There is a magnet for each complementary contact, the magnet being in the branch conductor connected to the 75 special contact in the box. When the box is operated, by breaking the glass front, a detent is retracted, the complementary contact or circuit-changing arm is shifted or forced down onto the wheel or movable 80 member, the special conductor is opened, and this results in starting the motor, the contact arm is released and drops onto the circuit-breaking wheel, where it is held by positive pressure and a circuit is closed through 85 holding magnets, thus locking out all the other circuit-breaking wheels of the series. Thus held, they cannot interfere with the signal first started.

The arrangement for holding and starting 90 the magnets and the circuit arrangements can best be explained by reference to the associated drawings.

As a signal initiating means, alternative or supplementary to the call box, there is 95 employed an automatic starting circuit, in which the well-known fire or heat-detecting wire is employed. This wire consists of a pair of conductors, one of, say, copper, coated with a metal or alloy having a low fusing 100

characteristic; as a cover for this there is a permeable insulating coating and outside this insulating cover there is a metal conductor or cover, like lead. When heat is applied to the exterior, the fusible alloy melts, the alloy permeates the insulating covering, and thus electrically connects the inner and outer conductor. This completes a circuit, shunts the magnet, and starts the transmitting apparatus into operation, just as would be done by the signal if manually started from the box.

It is to be understood that the use of a single motor, located at a central point and arranged to drive the movable members of a series of transmitters, is a great saving in expense as compared with placing regulated motors, one in each of a number of signal boxes.

In the accompanying drawings, Figure 1 is a complete schematic diagram of the arrangement of apparatus and circuits. Figs. 2 to 5, inclusive, show the structure of the call box. Fig. 6 is a detailed view of the cam wheel. Figs. 7 and 8 are detail views of the contacts in the motor-controlled circuit.

In Fig. 1 there is a shaft, *s*, driven by a motor, *m*. There is also shown, for simplicity of illustration, a gravity motor, *m*, operating directly on the shaft, *r*, on which is fixed a toothed wheel, 10, meshing with a wheel, 11, on shaft *s*. The wheels, 10 and 11, are so proportioned that the shaft, *s*, makes four revolutions to one of the shaft, *r*. A fly, *f*, on a separate shaft with toothed wheel, 14, which meshes with wheel 10, operates as a regulator. On the shaft there is shown characteristically different movable members of signal transmitters like circuit wheels, *c*, *d*, each forming a part of a signal transmitter and each coöperating with its complementary contact, *e*. The movable members, *c*, *d*, have a characteristically different arrangement of teeth, that is, teeth varying in their number, arrangement or grouping. The transmitting member or complementary contact, *e*, is composed of two springs, 21, 22, with contact points on the adjacent surfaces of the springs. Springs 21, 22, are separated by insulating material, *i*, and are normally in contact. Springs 21, 22, are carried on an angular lever, 23, pivoted at 20. On the short arm of lever 23 is a pin, 25, engaging a cam surface or groove, 26, in cam wheel, *k*. Cam wheel, *k*, is fixed on shaft, *t*, to which is fixed a toothed wheel, 13, meshing with pinion, 12, on shaft, *s*. The angular lever, 23, has a projection, 24, in position to engage with the hooked lever, 30, pivoted at 31.

Referring to circuit wheel, or transmitter, *c*, complementary contact *e*, is shown in

its normal position, where lever 30 engages the projection 24 to hold the member, *e*, in an elevated position. In each case lever 23 carries a circuit-closing arm, or contact, *g*, coöperating with fixed points 32 and 33 in holding circuit of battery 90 and magnet *v*, so arranged that when lever 23 is released, arm, *g*, electrically connects points 32 and 33. The cam, *k*, and the pin 25 are so arranged that the cam makes one complete rotation, holding the circuit-closing member, *e*, positively in operative electrical connection with the teeth of the circuit wheel. As shown in Fig. 6 pin 25 enters the slot in cam, *k*, at the gate or unison point, in the cam groove; at the end of a revolution of cam, *k*, lever, 23, is elevated by the cam and projection 24 engages the hook on arm 30. In case a second signal-box is operated before a preceding signal is completed, every other lever, 23, except that first started, is retained elevated until the first lever, 23, has been returned to normal position; this return of lever, 23, opens the holding circuit, including battery 90 and magnet *v*, and allows the second signal lever, 23, to drop (its lever 30 having been released by magnet *q*) and then pin 25 enters the cam groove, and its contact, *g*, closes the holding circuit again. Motor driven transmitters, *c*, *d*, are located in a separate station, as, for instance, in the basement of an office building. Upper floors in the office building are shown at *j* and *n*, and on each floor, *j*, or *n*, there are one or more signal-boxes 40. These signal boxes, 40, are electrically connected with electro-magnets controlling the operation of the transmitters, *c*, *d*, etc. Each lever, 30, pivoted at 31, is spring-retracted against the influence of magnets *q* and *v*; each lever 30 is provided with holding magnets, *v*, in parallel, in a separate circuit, including battery 90. Each magnet, *q*, is in a special conductor, 54, extending to contact 66 in box 40. Signal-box 40 has a lever with three arms, 60, 61, 62, pivoted at 63, and controlled by a spring as 64. There is a stop 113 controlled by helical retracting spring 112. The construction of the box is shown in Figs. 2 to 5 inclusive.

Referring to Figs. 2 to 5, there is a case 115 100, preferably of cast metal, having a door, 101, hinged at 102, and having an interior catch device, 103, which engages a hooked arm, 104, pivoted at 105. Arm 104 is retracted by spring, 106. Hook, 104, is turned 120 by a three-cornered key, inserted from the outside as shown at 107. In the door, 101, there is a sheet or section of frangible material like glass, 110, in position to block the outward thrust of detent 113. Detent 113 is forced outward toward and into engagement with glass, 110, by spring 112. Detent, 113, has a terminal, 111, in position to engage

glass sheet 110 and hold contact, z , in its set position. The contact, z , with its three arms, 60, 61, and 62, is pivoted at 63, and as stated spring 64 exerts its influence to snap contact, z , from the set position shown in Fig. 4, in engagement with contacts 65 and 66 into engagement with the lower contacts 67 and 68. Contacts 65 and 67 are electrically united by a conductor, 69. Contact 66 is the special conductor contact and contact 68 is a spare or extra contact. The position of contact, z , after it has been released by breaking the glass, 110, is shown in dotted line in Fig. 4. The inner end of detent 113, the end opposite terminal 111, rides on the surface or web, 91, uniting the three arms 60, 61, 62. In restoring contact, z , to its normal position, after replacing the sheet of glass which was broken in the process of transmitting a signal, the inner terminal of detent 113, is in engagement with the flat surface or web of contact, z , detent 113 is forced outward and the door can only be closed after contact, z , has been carried to its normal or vertical position, as shown in Fig. 4. The arrangement of contact, z , presents an unbroken surface at 91 and this surface 91 holds detent 113 in its projected position, thus preventing the closing of the door, which renders closing of the door impossible while contact, z , is in any intermediate position. With the construction and arrangement of contact, z , and detent 113, contact can only be restored and the door closed when the contact is in its normal or set position. Contact, z , has a snap-action under the influence of spring 64 so that when it is released by breaking the glass it passes with a snap from the normal position to the dotted line position shown in Fig. 4.

There are a series of signal boxes arranged on each floor; I prefer to place four on each floor; and each series of eight wheels, for instance, those on any two floors, are electrically connected with corresponding transmitters, the movable members of said transmitters being driven from a motor common to the series. I have shown, for illustration, one box on each of the two floors, j and n . The main battery is shown at 50. Wire 51 is the common return branch circuit. In branch circuit 51 there is a resistance coil 52, to prevent a short-circuit on the battery. The magnet q , controlling lever 30, is in a circuit extending from battery 50, via 53, q , 54, special contact 66, in box 40 arm 60, wire 58, arm 60 of box 40 on floor, n , to return circuit 51. By this arrangement the boxes are in a normally closed circuit, and any derangement may be immediately detected. Each box, therefore, controls its special branch circuit, 54, including magnet q . When the glass 110 is broken, detent 113

is released, contact, z , snaps on to contact 65 67, opening branch circuit 54, by breaking special branch circuit 54 at contact 65 and immediately closing the main circuit at contact 67. When magnet q , is thus deenergized, arm 30 is retracted and disengages its hooked terminal from hook 24 on lever 23; the complementary contact, e , is forced into engagement with the periphery of the movable member or signal wheel of the transmitter, pin 25 and cam groove 26 in wheel k 75 holds lever 23 in position to maintain member, e , in operative engagement with the circuit wheel; contact, g , simultaneously closes contacts 32 and 33 in a special circuit containing battery 90 and holding magnet v . 80 When this circuit of battery 90 is thus closed levers 30 of the operating transmitter and each and every other transmitter are held in a normal position so that if any signal-box is operated before the first started signal is completed, the transmitting device of such second signal will be inoperative. When magnet, q , of the first operated signal device released arm 30, contact, e , was forced down and circuit of motor starting magnet 208, 90 containing battery 201, was broken at normally closed scraping or rubbing contact points 202, the contacts 202 (Figs. 7 and 8), carried by lever 23, normally rested on the fixed conducting plate 212 (Fig. 8), and 95 when lever 23 assumed a depressed position contacts 202 moved down and were open, as shown in Fig. 7; it resulted that armature 203 of magnet 208, pivoted at 204, and retracted by spring 205, was withdrawn from 100 the path of fly, f , and the motor, m , started into operation. The indicating apparatus, 300, shown as a recorder, is in circuit with battery 301, in which the circuit-closing point 302 of signal transmitters c and d are 105 included in series. This recorder, 300, may be located in the same station with the motor device or in a separate and remote station. In the same circuit with recording magnet 300 are audible vibrating electro-magnetic alarm bells, like 320. Such alarms are located on each floor like those shown at j and n .

In order that the same signal described as initiated by breaking the glass door of a box 115 may be transmitted automatically from an alternative automatic circuit closer, I arrange on the wall or ceiling on each floor, the well-known fire-detecting wire, consisting of two parallel conductors separated 120 by a permeable insulating material and a fusible conductor, the arrangement being such that when the temperature is elevated, as by a conflagration, the easily fusible metal will melt and connect the two wires or conductors electrically. For this purpose I arrange to shunt the magnet q . The fire-detecting conductors are shown at x and y and

special conductors at 43 and 44. The conductor 44 extends from conductor, y , to the armature, 311, of magnet, 310, of an automatic electro-magnetic circuit-breaker, 5 through break point, 312, and the coil of magnet 310, to a point in conductor 54 on one side of magnet q . The conductor 43 extends from conductor x directly to a point in conductor 54 on the opposite side of magnet q . It results from this that when the fire-detecting wires x and y are electrically connected, the magnet, q , is cut out of circuit or short circuited, from one terminal of q , via 43, x , y , 44, 312, coil of magnet 310, to 15 the other terminal of magnet q . The current from battery 50 and wires 53 and 54 flows in this circuit, momentarily energizes the coil of magnet 310, its armature is attracted and the circuit is broken at point 312 20 by the dropping of the shutter.

The door-locking device is shown at 210 in Fig. 2; a triangular key is employed.

What I claim is:

1. In a fire-alarm telegraph the combination, at one station, of a circuit including signal indicating apparatus, a motor, a series of separately operative, characteristically different signal transmitters mechanically connected with said motor, and an electro-magnet 25 for controlling said motor, a series of controlling electro-magnets, one for each signal transmitter, a series of manually operated signal-boxes, each consisting of a snap-action member and three fixed contacts, so arranged, that said snap-action member, when released, opens a first and second circuit connections and then quickly closes the first-named connection, there being one signal-box for each transmitter, located at separated stations, respectively; a series of branch circuits each associated with one snap-action signal-box and one of said transmitters, and means whereby operation of a manually operated, snap-action signal-box starts the motor and at the same time renders the corresponding signal transmitter active and the others inactive.

2. The combination, in a fire-alarm signal apparatus of an indicating circuit, a series 50 of characteristically different signal transmitters at one station, each transmitter including a movable and a complementary member; a single motor device at said station for operating said movable members, a series of identical manually operated snap-action signal boxes at a series of separated points, one for each transmitter each of said boxes consisting of a snap-action member and three fixed contacts co-operating therewith, and means whereby the operation of any snap-action signal-box starts its corresponding signal transmitter and disables the other transmitters until the one first started has stopped.

3. In a fire-alarm signal, the combination 65 of an indicating circuit, a series of different signal transmitters, at one station, each transmitter consisting of a movable and a complementary member, a single motor device common to the series of transmitters, a series of manually operated starting boxes 70 at a series of separated stations, each box consisting of a snap-action movable contact and three fixed contacts, and means whereby the operation of any starting device releases its corresponding transmitter, electrically and mechanically disables the other transmitters during its operation and then releases a second transmitter, the snap-action signal-box of which was actuated during 80 operation of the transmitter corresponding to the first signal box actuated.

4. In a fire-alarm signal apparatus the combination of an indicating circuit, a series 85 of transmitters at one station, each consisting of a motor-driven member and a complementary member, a single motive power common to said series, a series of manually-operated snap-action starting devices at a series of separated points or stations, each 90 device having a spring arm and three fixed contacts and a frangible sheet to hold the spring arm at rest; and means whereby the fracture of said sheet at any starting device starts the motor to operate the corresponding transmitter and electrically restrains the other transmitters during operation of said transmitter.

5. In a fire alarm apparatus, the combination of an indicating circuit, a series of 100 automatic signal transmitters and a motive power common to the series at one station; a series of manually-operated signal-starting devices at a series of separated points, each of said devices consisting of a snap-action member and three fixed contacts, so arranged that said snap-action member, when released, opens a first and second circuit connections and then quickly closes the first-named connection, a main circuit connected to two of said fixed contacts and a special circuit connected to the third fixed contact, substantially as described.

6. In a fire alarm apparatus, the combination with circuits and apparatus for transmitting and indicating signals, of a substation, a manually-operated starting device including three fixed contacts and a snap-action contact, a spring for imparting snap-action to said contact, a spring retracted member for normally restraining said contact, and means for suddenly releasing said contact.

7. A starting device for fire alarm telegraph signals, including, in combination, a manually-operated snap-action contact and three fixed contacts, a spring retracted reciprocating member for normally restrain-

ing said contact and a fragile retaining device adapted to breaking action for suddenly releasing said contact.

8. A starting device for fire-alarm telegraphs, including, in combination, a snap action contact and three fixed contacts, a spring-actuated detent for normally restraining said movable contact, means for restraining and then suddenly releasing said

detent and means for holding said detent 10 out of action while the movable contact is passing one extreme position to the other, as during the process of resetting.

CHARLES A. HARSCH.
